UNITED STATES PATENT OFFICE.

HAROLD H. SIMMS, OF ROCHESTER, NEW YORK, ASSIGNOR TO AUTO STROP COMPANY,
OF NEW YORK, N. Y., A CORPORATION OF NEW YORK.

RAZOR.

1,133,327.

Specification of Letters Patent. Patented Mar. 30, 1915.

Original application filed April 17, 1909, Serial No. 490,564. Divided and this application filed September 23, 1909. Serial No. 519,218.

To all whom it may concern:

Be it known that I, HAROLD H. SIMMS, of Rochester, in the county of Monroe and State of New York, have invented certain new and useful Improvements in Razors; and I do hereby declare the following to be a full, clear, and exact description of the same, reference being had to the accompanying drawings, forming a part of this specification, and to the reference numerals marked thereon.

The present invention relates to razors, the subject matter of this application having been divided from an application filed by me on April 17, 1909, Serial No. 490,564.

The object of this invention is to provide a safety razor of simple construction having provision for stropping its blade without removing the latter from the holder which supports it during shaving.

To these and other ends the invention consists in certain improvements and combinations of parts all as will be hereinafter more fully described, the novel features being pointed out in the claims at the end of the specification.

In the drawings: Figure 1 shows an enlarged transverse section of one embodiment of the razor, with the parts in shaving position; Fig. 2 shows the same embodiment in an enlarged section longitudinally of the blade holder; and Fig. 3 is a side view of the razor with the parts in position for stropping.

In the illustrated embodiment there is provided a blade holder comprising a supporting member or plate 1 having blade positioning means or pins 2 projecting upwardly therefrom to pass through perforations in a blade 3 which may have two longitudinally extending cutting edges, the blade being held to the supporting plate by any suitable retaining means. In this instance the member or plate 4 engages the blade between its two cutting edges and is pivoted at one end as at 15 to the supporting member to turn about an axis transverse to the cutting edges of the blade, its other end being secured by a spring latch 6 preferably integral with plate 4 and adapted to coöperate with the walls of a recess or opening 7 in a proximate portion of the razor.

The blade holder may be supported away from its central portion so that a strop or other sharpener may engage the cutting

edges of a blade in the holder. In this instance it is supported at one end only by a frame 8 which may be integral with the supporting plate 1 and is formed with a space 9 opening toward the other end of the holder so that a strop may be introduced laterally into the space.

The handle, which may be of any construction, comprises in this embodiment a core 10 having a screw threaded end 11 and a knurled end 12, the core being surrounded by a grip portion or sleeve 13. Preferably the handle is secured to the frame to one side of the longitudinal axis or length of a blade in the holder. To this end the frame 70 has means permitting the handle to be secured thereto so as to lie perpendicular to the length of the blade, and also has means permitting the handle to be secured thereto so as to lie parallel with the blade. These 75 means are in this instance in the form of screw threaded portions 14 and 15 adapted to be engaged by the threaded end 11 of the handle. When the handle is secured to the threaded portion 14 the grip portion 13 is 80 engaged by a lug or projection 16 which enters a notch in the grip portion and prevents the turning of the latter, thus permitting the handle to be utilized for operating the razor for shaving or stropping. On 85 the other hand when the handle engages the threaded portion 15 the grip is free to rotate so that the blade holder may rock relatively thereto.

The latter arrangement of the handle and 90 the turning thereof are particularly advantageous in stropping, for when the blade holder with a double edged blade therein is caused to rest on a strop as shown in Fig. 3 the handle grip will lie below or to one side 95 of the plane of the blade so that the hand of the user in moving the device back and forth over the strop will cause the opposite edges of the blade to shift alternately and automatically into and out of coöperation with 100 the strop. Of course the blade edges are stropped only on one side, but the other side may be stropped by reversing the position of the blade in the holder.

The edges of the blade are preferably protected by two guards 17 formed along opposite edges of a guard frame 18 and each adapted to coöperate with an edge of a blade in the holder. The guard frame with its guards is movable relatively to the blade 110

holder in order to permit a blade in the latter to be engaged by a strop. In this instance the guard frame is entirely detachable from the other parts of the razor and 5 for this purpose has interlocking engagement at one end with the frame 8 as by a notch or recess 19 in the latter receiving a projection 20 on the guard frame, while at the other end the guard frame carries 10 a spring latch 21 having a deflected end 22 adapted to enter an opening 23 in the plate to coöperate with the inclined wall 24 of the latter. When the latch is in engagement with the blade holder it tends to move 15 the guard frame toward the other end of the blade, thus firmly holding the guard frame against the frame 8 to prevent vibrations during shaving. A pressure on the latch in the direction of the length of 20 the guard frame will move the deflected end 22 so that it may enter or pass from the opening 23, while a pressure downwardly on projection 25 at the end of the guard frame will carry the end 22 out of 25 engagement with the wall 24. After the latch has been released from engagement with the blade holder, the guard frame may be disengaged from the frame 8 to expose both edges of the blade. The blade may 30 now be brought to a strop or other sharpener or the handle may be first shifted to the threaded portion 15. In either instance the holder may be caused to rock so as to 35 present alternately opposite edges of the blade to the sharpener.

With a razor constructed in accordance with this invention the blade may be quickly stropped in the holder which is employed for supporting the blade during 40 shaving and the adjustments necessary to secure these results are few and simple. The blade is rigidly held to the supporting frame so it is possible to secure any pressure on its edges that may be desirable.

45 I claim as my invention:

1. In a safety razor, the combination with 50 a double-edged blade, and a blade supporting member for supporting the double-edged blade to expose both edges, of a handle having a connection with the supporting member at one end only and symmetrically arranged with relation to opposite sides of the member, a pair of guards for coöperation with the exposed edges of the 55 blade, means for permitting the movement of the guards relatively to the supporting member and to the handle to carry the guards away from the double-edged blade while the latter is clamped to the blade supporting member, and means for clamping the blade to the blade-supporting member, said means being effective as clamping means when the guards are moved away from the supporting member.

60 2. In a safety razor, the combination with

a blade-supporting plate and a blade supported on said plate with its opposite edges projecting from opposite sides of the plate, of a handle secured to one end only of the plate and symmetrically with relation to 70 the opposite edges of the latter, a pair of guards for the projecting edges of the blade, means permitting the guards to be moved relatively to the supporting plate and to the handle, and means for clamping the blade against the supporting plate, said means being effective as a blade-clamping means when the guards are moved away from the supporting plate.

3. In a safety razor, the combination with 80 a blade holder having means for securing a double edged blade between its two edges, of a handle arranged symmetrically with relation to opposite sides of the holder and perpendicularly to the plane of said holder, 85 a connection between the handle and the blade holder provided with a space beneath the blade holder for the passage of a sharpener, a pair of guards for the blade edges, and means permitting such guards 90 to be moved relatively to the holder and the handle to clear the space beneath the blade holder.

4. In a safety razor, the combination with 95 a blade, a blade-supporting plate, and means for clamping the blade against one surface of such plate to cause the blade to project from opposite edges of said plate, of a handle symmetrically arranged with 100 relation to the opposite edges of said plate and also perpendicular to said plate, a rigid connection between the handle and the plate provided with a space on the side of the plate opposite the blade for the passage 105 of a sharpener, a pair of guards, and means permitting said guards to be moved so that a sharpener may be passed through the space of the connection.

5. In a safety razor, the combination with 110 a supporting plate, a blade, and means for clamping the blade against one side of the plate, of a guard arranged on the other side of the plate, a latch detachably securing said guard in position, and a handle secured to said supporting plate only at one end of the latter in proximity to one end of the cutting edge of the blade so that, when the guard is removed, the blade may be stropped.

6. In a safety razor, the combination with 120 a blade holder having means for securing a double edge blade while exposing both edges, of a handle secured to one end only of said blade holder and arranged symmetrically with relation to opposite sides of 125 said holder, a guard frame having guards on opposite sides for coöperation with the blade edges and detachable from the holder and the handle, and a latch for securing the guard frame beneath the blade holder.

7. In a safety razor, the combination with a supporting plate, of a handle secured to one end only of said plate, symmetrically with relation to opposite sides of the plate, 5 means for clamping a blade against the plate, a guard frame having guards on opposite sides coöperating with opposite edges of the supporting plate and detachable from the holder and the handle, and means 10 detachably securing said guard frame on the side of the supporting plate opposite that on which the blade is held.

8. In a safety razor, the combination with a supporting member, a double-edged blade 15 supported by said member between its two edges, and a handle having connection with one end only of the supporting member, of a guard frame having two guards each adapted to coöperate with an edge of the 20 blade on the supporting member, means detachably-securing the guard frame in co-operative relation with the blade, and means for clamping the blade to the supporting member, said means being effective as a 25 blade clamping means when the guard frame is detached from the device.

9. The combination with a blade holder a blade supporting plate, and means for clamping the blade against the plate, of a 30 frame for supporting the same secured to the latter near one end only and having a space for the passage of the strop, opening at the other end of the holder, a handle arranged on said frame perpendicular to the 35 length of a blade in the holder, a guard for a blade in the holder and means permitting the guard to move relatively to the handle to expose the said blade for stropping.

10. The combination with a blade holder 40 embodying a supporting plate and means for retaining a blade thereon, of a frame rigidly secured at one end to the supporting plate and having a space below the latter opening toward the opposite end for the 45 passage of a strop, a handle arranged on the frame perpendicular to the length of a blade in the holder, a guard for a blade in the holder and means permitting the guard to move relatively to the handle to expose 50 the blade for stropping.

11. The combination with a blade holder comprising a supporting plate and means for clamping a blade to said plate, a guard, and means permitting one of said parts to move bodily relatively to the other to permit the blade to be engaged by a strop, of a supporting frame for the blade holder rigidly secured to the latter at one end only and having a space below the blade holder opening at the other end of the latter, and 60 a handle secured to said frame perpendicular to the length of a blade in the holder.

12. The combination with a blade holder, of a frame for supporting the same having a space for the passage of a strop, a handle, 65 means permitting the handle to be secured to the frame so that its length lies transverse to the length of a blade in the holder, and means permitting said handle to be secured to the frame so that its length lies 70 parallel to the length of a blade in the holder and a guard movable relatively to the blade holder and the handle in both positions of the latter.

13. The combination with a blade holder 75 embodying a supporting plate, a double edged blade, and means for clamping said blade on one side of the plate to project from opposite sides of the plate, of a handle having connection with one end only of said 80 plate, and a guard frame movably arranged on the other side of said supporting plate and having guards for coöperating with both edges of the blade.

14. The combination with a blade holder 85 for a double edged blade comprising a blade supporting plate and means for clamping a blade thereto, of a frame rigidly secured to said blade supporting plate and having a space for the passage of a strop to engage 90 a blade in the holder, a handle, means for securing said handle to the frame so that the handle lies parallel with the length of a blade in the holder, guards for the blade edges and means permitting said guards to 95 move to expose the latter.
